UNITED STATES PATENT OFFICE.

KENNETH J. UNWIN, OF SHREWSBURY, MASSACHUSETTS, ASSIGNOR TO CROMPTON & KNOWLES LOOM WORKS, OF WORCESTER, MASSACHUSETTS, A CORPORATION OF MASSACHUSETTS.

MOUNTING FOR LOOM SPINDLES.

Application filed December 22, 1926. Serial No. 156,472.

This invention relates to means for mounting the spindles for loom pickers and it is the general object of the invention to provide a very simple mounting wherein the inner and outer ends of the spindle may be held tightly with respect to the lay and any wear taken up by means of a single adjusting member.

In box looms and on the plain ends of some weft replenishing looms, the propelling force for the shuttle is transmitted from the picker stick through a so-called picker which slides along a cylindrical guide known as the spindle. Experience shows that the spindle, due to constant vibration of the picking motion, is subject to wear and becomes loose and it is an important object of my present invention to provide means for taking up any resultant looseness at both ends of the spindle by a single means. In co-pending application #155,742 filed by Parent there is shown a clamping member having split portions and inclined surfaces so related that the spindle will be held tightly by the split part of the support when the latter is moved relatively to fixed inclined surfaces, this mode of support being employed for the inner end of the spindle. In Patent #1,594,620 granted to Lanciault there is shown a screw in line with the axis of the spindle and threaded into a fixed portion of the lay, said screw being movable to take up wear on the ends of the spindle.

It is a further object of my invention to combine the structures shown in said application and said patent and employ the screw shown in the Lanciault construction for compressing the split portions of the clamping element shown in the Parent application to the end that said screw may be effective to hold both ends of the spindle tightly.

With these and other objects which will appear as the description proceeds, my invention relates to the arrangements and combinations of parts hereinafter set forth, and more particularly pointed out in the claims.

In the accompanying drawings, wherein a convenient embodiment of my invention is shown,

Fig. 1 is a top plan view of a portion of the lay having my invention applied thereto,

Fig. 2 is a rear elevation looking in the direction of arrow 2 in Fig. 1,

Fig. 3 is an enlarged vertical section on line 3—3 of Fig. 1, parts being removed for the sake of clearness, and

Fig. 4 is a vertical transverse section on line 4—4 of Fig. 3.

Referring to the drawings the lay 10 is provided with a lay end 11 and lay sword 12 and may be provided with box guides 13. Shuttle boxes 14 accommodate shuttles S and may be moved vertically by mechanism not shown, so that either shuttle may become active. A spindle 15 has slidably mounted thereon picker 16 provided with a shuttle engaging portion 17 and having engagement with picker stick 18. During each pick of the loom when the lay is substantially on top center the picker stick will be moved to the right from the position shown in Figs. 1 and 2, to pick the shuttle through the shed, the picker moving along and being guided by the spindle 15. This part of the construction is very old and forms no part of my present invention.

The support for the outer end of the spindle is identical with that shown in the aforesaid Lanciault patent, the lay having a threaded bore 20 formed in a block 21 secured to the lay end. The spindle 15 projects into one end of the bore 20 and the holding screw 22 is threaded into the other end of said bore, a lock nut 23 being employed to check accidental movement of screw 22. The latter is in tight contact with the left hand end of the spindle 15 and is the means by which longitudinal movement of the spindle may be effected. The spindle is inserted through the bore 21 when being assembled and may be withdrawn through said bore by the removal of screw 22.

The inner end of the spindle is supported by mechanism similar to that shown in the aforesaid Parent application and employs the usual lug 30 customarily cast integral with lay end 11. Said lug has a bore a portion of which is cylindrical as indicated at 31, and a portion of which is conical as at 32. A clamping member designated generally at 33 has a cylindrical bore 34 of substantially the same diameter as the external diameter of the spindle 15, and the member 33 is provided with an exterior conical surface 35 which is in contact with the interior conical surface 32 of lug 30. That portion of the clamping member 33 adjacent to the bore 34 is split as indicated at 36 to provide said

clamping member with a plurality of resilient elements 37 which are movable independently of each other and compressible to vary the diameter of bore 34.

5 In assembling the device the spindle, which may have both ends thereof square as indicated in the drawings and without the customary taper on one end, is inserted through the bore 20, as previously described, 10 and into the cylindrical bore 34 of the clamping member 33. The screw 22 is then threaded into the bore 20 and forced against the left hand end of the spindle 15. This moves the right end of the spindle to the right hand 15 end of the bore 34 into engagement with the solid portion of the clamp 33. The latter is, therefore, moved slightly relatively to the lug 30 and the cooperating inclined surfaces 32 and 35 co-act to compress the elements 37 20 against the right hand end of the spindle 15. When both ends of the spindle have been made sufficiently tight, the check nut 23 may be positioned as shown in Fig. 3 to prevent accidental movement either of the screw 22 25 or the clamp 33.

From the foregoing it will be seen that I have provided a very simple means for securing both ends of the picker spindle with respect to the lay, the spindle being formed 30 with square ends and being free from the customary conical tip usually provided on the inner ends of the spindles. It will be seen that the screw 22 serves not only to prevent displacement of the spindle to the left, but is also the means by which the clamping member is forced into close holding 35 engagement with the spindle.

Having thus described my invention it will be apparent that changes and modifica-

tions may be made therein by those skilled 40 in the art without departing from the spirit and scope of the invention, and I do not wish to be limited to the details herein disclosed but what I claim is:

1. In a mounting for loom picker spindles, a lay, inclined surfaces fixed with respect to the lay, a clamping member having inclined surfaces to co-act with the inclined surfaces of the lay, said member having a bore to receive one end of the spindle, a plurality of independently movable and slightly compressible elements formed with the member and lying around the bore, and a screw threaded into a part of the lay and engaging the other end of the spindle and capable of moving the said spindle in a direction toward the member to cause said inclined surfaces to force the slightly compressible elements against the spindle and hold the same, said screw thereby preventing loosening of both ends of the spindle.

2. In a loom having a lay provided with an opening having inclined sides, a spindle clamp extending into the opening and having the outer surface thereof inclined to conform to the opening in the lay, said clamp having a bore therein, a plurality of slightly resilient elements formed integrally with the clamp surrounding and defining the bore, a picker spindle having one end projecting into the bore and means acting on the other end of the spindle to force the clamp into the opening in the lay to force the elements against the spindle to hold the latter in place.

In testimony whereof I have hereunto affixed my signature.

KENNETH J. UNWIN.
